UNITED STATES PATENT OFFICE

2,612,901

TIME AND HUMIDITY CONTROLLED FLUID DISPENSING SYSTEM

Peter J. Milano, Salt Lake City, Utah

Application June 5, 1947, Serial No. 752,745

5 Claims. (Cl. 137—78)

1

This invention relates to new and useful improvements in automatic fluid dispensing apparatus and the primary object of the present invention is to provide a device that will efficiently and automatically supply fluid to a discharge point without supervision.

Another important object of the present invention is to provide a fluid dispensing apparatus that includes electrical as well as manual means whereby the fluid distributed may be controlled.

A further object of the present invention is to provide an automatic fluid dispensing apparatus including a time control mechanism whereby the flow of fluid may be regulated for any length of time and at a selected time.

A still further aim of the present invention is to provide an apparatus for the foregoing purposes that is simple and practical in construction, efficient and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary diagrammatic front elevational view of the present invention;

Figure 2 is a fragmentary side elevational view of the distributor valve means;

Figure 3 is an enlarged vertical sectional view taken on the line 3—3 of Figure 2;

Figure 4 is a perspective view of the humidity control mechanism;

Figure 5 is a perspective view of the control valve mounted in the distributor; and,

Figure 6 is a longitudinal vertical sectional view taken on line 6—6 of Figure 5.

Referring now to the drawings in detail, wherein for the purpose of illustration, there is disclosed a preferred embodiment of the present invention, the numeral 10 represents a support on which is mounted a distributor housing 12 having a pair of removable end plates 14.

Extending substantially through the center of the housing and journaled in bearings 16 carried by the hub portion 18 provided at the outer faces of plates 14, is a drive shaft 20.

Mounted on shaft 20 within housing 12 is the hub 21 of a rotary disc-like valve member 22, provided with an arcuate slot 24 in its flanged portion 26, that selectively communicates with a plurality of outlet mains 28 carried by the distributor housing 12.

A plurality of circumferentially spaced apertures 30 are also provided in member 22 to prevent entering pressure from locking member 22 to the housing and thus these apertures also permit a smooth undisturbed rotation of the valve.

2

Operatively connected to shaft 20 by a clutch mechanism 32, is a speed reduction gear mechanism designated generally by the numeral 34, that is operated by an electric motor 36. The clutch mechanism permits the gear mechanism 34 to rotate the shaft 20 in one direction only.

A supply main 38 for the distributor is interposed between the distributor and a source of fluid for supplying fluid to the distributor. This main 38 is provided with an air buoy or stack 40 closed by removable cap 42 that tends to prevent "water hammer" in the main 38.

Mounted in the fluid supply main 38 is a solenoid operating valve 44 that is connected by electrical lines 46 to a source of electric power for operating the valve in closing and opening the supply main 38.

A by-pass 48 around valve 44 includes a manually operated valve 50 for manually regulating the flow of fluid from the main 38 to the distributor housing.

Mounted in series with the solenoid valve 44 is a time control mechanism 52 for controlling said valve 44. This time control mechanism is also connected in series to motor 36 for simultaneously controlling the operating period for said motor and the opening period for valve 44.

Connected in series to the time control mechanism is a mercury control mechanism designated generally by the numeral 54. This mercury control mechanism or humidifier 54 includes a canvas belt 56 interlaced with pegs 58 carried by an anchor plate 60. One end of the belt is secured to a housing 62 carried by the plate 60 at one end and the other end of belt 56 is connected to a coil spring 64 mounted within housing 62. The tension of said spring 64 is adjustable by set screws or the like 66.

Pivotedly mounted within the housing 62 is a mercury tube 68 provided with an outwardly projecting arm 70 that is suitably connected to the spring 64 adjacent the end of belt 56. A stop and support 72 carried by the housing supports the lower end of tube 68 when the electrical circuit system is open and limits pivotal movement of the tube within the housing.

In practical use of the device, the humidifier 54 is mounted outdoors and when the weather conditions are dry, the canvas belt is contracted to over-balance the spring 64 causing the mercury tube to tilt toward the belt and closing the circuit between motor 36, time control mechanism 52, and valve 44, thereby causing a flow of fluid into the distributor housing.

Humidified air tends to expand the belt and spring 64 tilts the tube in an opposite direction, rolling the mercury in the tube away from the submerged contacts in the tube thus opening the electrical circuit and rendering the device inoperative regardless of the time switch mechanism.

In operation of the device, the time mechanism is set to the desired time for which the device is to be energized, at this set time the opening 24 in valve member 22 communicates with one of the outlet mains 28 for causing a time regulated flow of fluid through said outlet main. As the valve continues rotation, opening 24 then communicates with another of said mains 28 for likewise controlling the time flow through the mains. However, as previously stated should the atmospheric condition be wet, the humidity control mechanism will automatically cut off the solenoid valve 44 so that water or fluid will not be wasted for sprinkling a lawn or the like.

For manual use of the device, the valve 50 is turned on and by rotating shaft 20 by hand wheel 14, the flow of fluid through the outlet mains 28 may be selectively controlled.

Obviously, clutch 32 is disengaged with the gear mechanism 34 so that the shaft 20 may be conveniently rotated manually without devolving the gear mechanism.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. An automatic fluid dispensing apparatus comprising, a distributor housing, a plurality of delivery pipes leading outwardly from said housing, a disc-like distributor valve rotatably mounted in said housing and having an annular flange, said annular flange having an arcuate opening for communicating with said delivery pipes sequentially, means for rotating said valve, an electrical time mechanism operatively connected to and controlling said valve rotating means, a supply pipe connected to said housing for supplying a fluid to said valve, a further valve controlling the flow of fluid through said supply pipe, means responsive to the moisture content of a surrounding gaseous medium and operatively connected to said further valve and to said first-mentioned connection for actuating said further valve, a by-pass about said further valve, and a manually operated valve controlling said by-pass.

2. An automatic fluid dispensing apparatus comprising, a distributor housing, a supply line connected to said housing, a plurality of delivery conduits leading from said housing, a valve rotatable in said housing and having a port for successively communicating with said conduits, power means operatively connected to said valve for rotating the latter, a time control mechanism controlling said power means, a valve for the supply line, a solenoid connected to the last-named valve for actuating the last-named valve, and means responsive to the moisture content of a surrounding gaseous medium and electrically connected to said solenoid and to said time control mechanism for actuating said solenoid.

3. An automatic fluid dispenser comprising, a distributor housing, a supply line connected to said housing, a plurality of delivery conduits

leading from said housing, a valve rotatable in said housing and having a port for successively communicating with said conduits, an electrically operated power means connected to and rotating said valve, a pair of circuit wires connecting said power means to a source of electric current, an electrical timer interposed in the circuit wires in series with said power means, a switch also connected to said wires between and in series with said timer and power means, means responsive to the moisture content of a surrounding gaseous medium and connected to the switch for actuating the latter, and a solenoid operated valve in the supply line and connected to the circuit wires between said switch and power means and in parallel with said power means.

4. An automatic fluid dispenser comprising, a distributor housing, a supply line connected to said housing, a plurality of delivery conduits leading from said housing, a valve rotatable in said housing and having a port for successively communicating with said conduits, an electrically operated power means connected to and rotating said valve, a pair of circuit wires connecting said power means to a source of electric current, an electrical timer interposed in the circuit wires in series with said power means, a mercury switch connected to the circuit wires between and in series with said timer and power means, a means responsive to the moisture content of a surrounding gaseous medium and connected to said mercury switch for actuating the latter to its circuit-open position to break the circuit to the power means, a valve controlling the flow of fluid through the supply line, and a solenoid connected to the last-named valve and electrically connected to the circuit wires between said switch and power means and in parallel with said power means.

5. An automatic fluid dispensing apparatus comprising a source of fluid, a distributor housing connected to said source, a plurality of delivery pipes leading from said housing, a valve rotatable in said housing for controlling the flow of fluid through said delivery pipes, power means operatively connected to and rotating said valve, a time mechanism electrically connected to said power means, a solenoid operated valve for controlling the flow of fluid to said housing, and means responsive to the moisture content of a surrounding gaseous medium and electrically connected to said solenoid and to said first-mentioned connection for actuating the last-named valve.
